ABSTRACT

A floating mandrel for drawing welded tubes with longitudinal seam, comprising two cylindrical sections of different diameters interconnected by a tapered section. One cylindrical section having a larger diameter incorporates a guiding slot while the other section having a smaller diameter incorporates a through-hole extended to the surface of the mandrel which contacts the tube, thus forming a cutting edge. This edge is encompassed by a groove made in the contacting surface and extended to the cylindrical section having a larger diameter.

FIG. 3

FLOATING MANDREL FOR DRAWING WELDED TUBES WITH LONGITUDINAL SEAM

The present invention relates to the tube production and more exactly to floating mandrels for drawing welded tubes with longitudinal seam.

The present invention may be most efficiently utilized in drawing thin-walled tubes made from materials tending to excessive sticking, such as aluminium and its alloys.

Floating mandrels are known at the present time for drawing welded tubes with longitudinal seam, comprising two cylindrical sections of different diameters of interconnected by a tapered section with one section of a larger diameter incorporating a longitudinal guiding slot to orient the mandrel with respect to the internal flash and with the other section of a smaller diameter incorporating a through-hole to pass the removed internal flash into the drawn portion of the tube, the latter hole directed from the end face of this section towards the guiding slot and extended to the surface contacting the tube, thus forming a cutting edge of the mandrel (cf., see USSR Author's Certificate No. 300,232 cl. B 21 c, 3/16).

In drawing tubes using known mandrels, the section of the inner surface of the tube corresponding to a spot from which flash has been removed enters the wall reduction zone with minimum amount of lubricant because the major portion of this lubricant is carried away together with flash removed. Therefore in drawing tubes made from materials tending to excessive sticking, seizing occurs between the metal and the contacting surface of the mandrel, which results in notches and scores on the inner surface of the tube in the flash removal zone thus reducing the quality of this inner surface.

The object of the present invention is to obviate the above disadvantage.

An important object of the invention is to provide a mandrel for drawing welded tubes capable of obtaining the inner surface of the tube of the required quality with simultaneous removal of internal flash by way of maintaining the needed amount of lubricant in the wall reduction zone over the entire perimeter of the tube.

These and other objects are achieved due to the provision of a floating mandrel for drawing welded tubes comprising two cylindrical sections of different diameters interconnected by a tapered section with one of them of a larger diameter incorporating a longitudinal guiding slot to orient the mandrel with respect to the internal flash and with the other of a smaller diameter incorporating a through-hole to pass the internal flash removed in the course of drawing, into the drawn portion of the tube, the latter hole being directed from the end face of this section towards the guiding slot and extended to the surface of the mandrel which contacts the tube, thus forming a cutting edge, according to the invention the surface of the mandrel contacting the tube incorporates a groove encompassing the cutting edge and extended to the cylindrical section of the larger diameter.

This design of the mandrel is capable of obtaining the inner surface of the tube of the required quality because the groove made in the surface of the mandrel contacting the tube brings lubricant in the course of drawing to that section of the tube from which flash has

just been removed, thus preventing metal sticking on the surface of the mandrel contacting the tube.

Conveniently the groove takes the shape of a second-order curve whose vertex is away from the cutting edge through a distance equal to 0.2 to 2.0 of the thickness of the tube wall while its legs are inclined in relation to the guiding slot at an angle of 15° to 45°.

Significantly important with this groove is its shape and positioning in relation to the cutting edge. Their best relative arrangement is when this groove delivers the sufficient amount of lubricant without substantial decrease in the strength of the mandrel. All these requirements are fully met with the above configuration of the groove. Moreover, arrangement of the groove legs at an angle to the longitudinal slot helps to obtain the tube inner surface of the required quality.

However, if the above limits are not observed by locating the vertex of the curve away from the cutting edge through a distance exceeding 2.0 times the value of the tube wall thickness or less than 0.2 of said value the reduction zone will lack lubricant or the mandrel be of less stability. Location of the curve legs at a larger than 45° angle will lead to an insufficient amount of lubricant brought to the tube section which has been freed from flash. This will be caused by the extended length of the groove and by carrying away a certain amount of lubricant by the passing adjacent sections of the tube. On the other hand, location of the curve legs at a less than 15° angle may cause clogging of the curve with the tube metal at the point where the reduction zone begins.

In order to make the invention more readily understood a specific embodiment thereof will now be described with reference to the accompanying drawings, in which:

FIG. 1 is a fragmentary cutaway view of the mandrel according to the invention;

FIG. 2 is a plan view of the mandrel shown in FIG. 1;

FIG. 3 shows the same mandrel in the course of tube drawing.

The mandrel comprises two cylindrical sections 1 and 2 (FIG. 1) of different diameters with the section 1 having a larger diameter and the section 2 — a smaller diameter. Both these sections are interconnected by a tapered section 3. The section 1 incorporates a longitudinal guiding slot 4 to orient the mandrel with respect to the internal flash, while the sections 2 and 3 incorporate a through-hole 5 to pass a removed internal flash 6 into a drawn portion of a tube 7 (FIG. 3). This hole is directed from an end face 8 (FIG. 2) of the section 2 towards the guiding slot 4 and extended to a surface 9 of the mandrel contacting the tube 8, thus forming a cutting edge 10.

The surface 9 incorporates a groove 11 encompassing the cutting edge 10 and extended to the cylindrical section 1. This groove brings the sufficient amount of lubricant to the tube wall reduction zone, thus preventing metal sticking on the surface 9 of the mandrel contacting the tube.

To avoid any substantial reduction in the strength of the mandrel the groove is given a second-order curve configuration such as that of a parabola shown in FIG. 2.

The vertex "A" of the parabola is away from the cutting edge 10 through a distance "a" which is equal to 0.2 to 2.0 of the thickness "S" of the wall of the tube

7. Legs "B" of this parabola are inclined in relation to the guiding slot 4 at an angle " α " within the range of 15° to 45° .

EXAMPLE

Drawing of welded tubes of diameter $d = 55$ mm and wall thickness $S = 1.65$ mm to obtain the tube size of diameter $d = 50$ mm and wall thickness $S = 1.5$ mm made from an alloy based on aluminium with the addition of Cu 3.8-4.9 percent, Mg 0.4-1.8 percent, Mn 0.3-0.9 percent, admixtures making up the balance, is effected by means of a mandrel incorporating a parabolic-shaped groove.

The vertex of the parabola is away from the cutting edge of the mandrel through a distance $a = 1.5$ mm while its legs are inclined in relation to the longitudinal guiding slot at an angle $\alpha = 25^\circ$. This mandrel is capable of obtaining tubes with the inner surface of high quality due to the delivery of the sufficient amount of lubricant via the circular lubricating groove to the reduction zone.

What we claim is:

1. A floating mandrel for drawing welded tubes with longitudinal seam, comprising: two cylindrical sections of different diameters; a tapered section interconnect-

25

ing the cylindrical sections, said sections having a surface contacting an inner surface of the tube, one of said cylindrical sections having a larger diameter, the second cylindrical section having a smaller diameter and an end face; a longitudinal guiding slot to arrange the mandrel with respect to an internal flash in said second cylindrical section having a larger diameter; a through-hole to pass the internal flash removed in the course of drawing into the drawn portion of the tube in said cylindrical section having the larger diameter and directed from the end face of this section towards the guiding slot and extending to said surface of the mandrel with contacts the tube, thus forming a cutting edge; a groove in said contacting surface and encompassing said cutting edge and extending to said cylindrical section having the larger diameter to pass lubricant applied in advance to the inner surface of the tube to the reduction zone behind said cutting edge in the course of drawing.

2. A mandrel as set forth in claim 1, wherein said groove has the configuration of a second-order curve whose vertex is away from the cutting edge through a distance of 0.2 to 2.0 of the thickness of the tube wall while the legs thereof are inclined in relation to the longitudinal slot at an angle of 15° to 45° .
